UNITED STATES PATENT OFFICE.

THOMAS CUSACK, OF CHICAGO, ILLINOIS, ASSIGNOR TO THOS. CUSACK COMPANY, OF CHICAGO, ILLINOIS, A CORPORATION OF NEW JERSEY.

HEADPLATE FOR SIGNBOARDS.

1,384,743.

Specification of Letters Patent. Patented July 19, 1921.

Application filed April 22, 1921. Serial No. 463,726.

To all whom it may concern:

Be it known that I, THOMAS CUSACK, a citizen of the United States, and a resident of Chicago, county of Cook, and State of Illinois, have invented certain new and useful Improvements in Headplates for Signboards; and I do hereby declare that the following is a full, clear, and exact description thereof, reference being had to the accompanying drawings, and to the letters of reference marked thereon, which form a part of this specification.

This invention relates to improvements in head plates for signboards, and consists of the matters hereinafter described and more particularly pointed out in the appended claims.

In the case of signboards, bill boards, bulletin boards, and other boards bearing advertising matter, it is customary and desirable for the proprietor and lessor of the board, who is also usually the one who applies the advertising or other matter to the board, to show his name on a name plate, either separate from or made a part of the board, to identify both his ownership of the board and also the origin of the work on the board.

It is desirable that the plate or imprint containing the name of the owner or lessor of the board be made up in quantities to be held on hand ready for use when a signboard is erected, this being required both for ease in erection, and also for general uniformity in the appearance of the imprint.

Separate head plates or head pieces, capable, by suitable means, of ready attachment to the top of a signboard, have been heretofore used, but such head plates, while possessing many advantages, are objectionable in that the imprint is presented as a separate and distinct part or addition to the signboard, which detracts from the unity of the signboard in its esthetic effect as a whole.

The object of the present invention is to provide a head piece adapted to bear an imprint containing the name of the owner or lessor of the board, which piece is so designed and constructed that it is not only quickly and easily attached to the signboard, but when attached, it will become such a part of the signboard, that it will continue and bear out the artistic panel effect

of the signboard as a whole. The improved sign piece or plate is so constructed and arranged that it may be made up in advance in quantities and held in stock, all pieces being of uniform size and construction, and being ready for instant and easy attachment, when a signboard is erected. The advantages of the invention will appear as I proceed with my specification.

In the drawings:—

Figure 1 is a view of the top part of a signboard with my improved head plate or head piece attached and in place.

Fig. 2 is a rear view of Fig. 1.

Fig. 3 is a front view showing the imprint part removed from the body of the sign.

Fig. 4 is a vertical section through Fig. 2 in a plane indicated by the line 4—4 of Fig. 2.

Fig. 5 is a vertical section through the head plate when removed from the sign.

Referring now to the drawings:—10 indicates a signboard, and 11 indicates the improved head plate or head piece. The signboard is of simple character, comprising upright end posts 12, 12, and an intermediate panel 13. The panel 13 is outlined at the top by means of a horizontal bar or strip 14.

The said bar 14 is generally and preferably provided along its top edge with a molding 15. This molding extends the full length of the signboard from post 12 to post 12 except for a gap 16 (see Fig. 3) where it is interrupted to leave space for the insertion of the head plate 11.

The head plate 11 comprises a narrow strip 17 of the same thickness as the thickness of the bar or strip 14, and an imprint plate 18, preferably of sheet metal, which is attached at its upper edge to the bar 17, and which depends below the bottom edge of said bar. The bar 17 is of a length adapted to fill the gap 16, and is provided along its top edge with a molding 19, identical with the molding 15 on the sign. Said molding is continued along the ends of the bar 17 by parts 19^a, 19^a, which depend below the bottom edge of the bar 17. The molding parts 19^a, 19^a, and the molding piece 15 at the gap 16, are cut to fit as by a miter joint 20, so that when the strip 17 is brought to rest on top of the strip 14 of the sign, the molding parts 19^a, 19^a will engage the

front face of the strip 14 and join the molding 15, so that the molding on the head plate will bridge the gap in the molding on the sign and produce a continuous effect.

5 To the back of the strip 17 of the head plate, are attached upright bars or plates 21, preferably three in number, namely, one at each end and one in the middle. Said bars depend well below the bottom edge of 10 the bar 17, and are adapted for engagement with the back face of the sign to which they are attached in any suitable manner, as by 15 screws or nails.

When applied in the manner described, 15 the imprint plate 18 will engage the front face of the bar 14, to which it is nailed. The imprint plate 18 is made of such vertical dimensions that when in place its bottom edge will lie somewhat above the bottom edge of the bar 14, as shown in Fig. 1.

When the head piece is applied as described, it will manifestly become such a part of the signboard that it will carry out the intended panel effect of the bar 14, and 25 will present the imprint plate 18 in the band or border presented by the bar 14, and this without destroying or detracting from the unity of the panel effect defined by the bar 14.

30 I claim as my invention:—

1. In combination with a signboard, which includes a panel and a bar defining said panel at the top, an auxiliary head-bar, a plate attached to the face of said head-bar

and depending below the bottom edge of 35 the same, and narrow, vertically extending bars secured to the rear face of said head-bar, said head plate and vertical bars being adapted to engage and to be secured to the opposite faces of the top bar of the 40 sign.

2. In combination with a signboard, which includes a panel, a bar defining said panel at the top, and a molding extending along the top edge of said bar provided with a 45 gap intermediate its ends, an auxiliary head-bar, a plate attached to the face of said head-bar and depending below the bottom edge of the same, a molding extending along the top edge of said auxiliary bar and having vertical parts at its ends, and narrow, 50 vertically extending bars secured to the rear face of said head-bar, said plate and vertical bars being adapted to engage and to be secured to the opposite faces of the top 55 bar of the sign, and said molding of the auxiliary bar being constructed to bridge the aforesaid gap in the molding on said top bar and to form a continuation of the same.

In testimony that I claim the foregoing as my invention, I affix my signature in the presence of two witnesses, this 16th day of April, A. D. 1921.

THOMAS CUSACK.
